(57) CLAIM

The ornamental design for spectacles, as shown and described.

DESCRIPTION

FIG. 1 is a front perspective of spectacles, showing my new design;

FIG. 2 is a front view thereof;

FIG. 3 is a rear view thereof;

FIG. 4 is a side view thereof;

FIG. 5 is a side view thereof, opposite that of FIG. 4;

FIG. 6 is a top view thereof; and,

FIG. 7 is a bottom view thereof.

The evenly dashed broken lines illustrate portions of the spectacles that form no part of the claimed design.
